RUNNING BOARD FOR CARS

Leon J. Lieberman, Philadelphia, Pa., assignor
to Alan Wood Steel Company, Conshohocken,
Pa., a corporation of Pennsylvania

Application July 1, 1940, Serial No. 343,339

8 Claims. (Cl. 105—457)

My invention is an improved running board designed to provide, over the top of a car, a rigid walkway composed of metal sheets free from substantial molecular distortion, which is reenforced against transverse stresses, and which affords a secure footing, available emergency hand holds, and which is automatically cleared of snow, ice and water.

My improved running board is particularly applicable to covered freight cars, such as box cars, house cars, and covered hopper cars, having roof sheets inclined downwardly and outwardly from a longitudinal median ridge. It is composed of a series of flanged, rigid, rolled steel plates spaced above the apex of the car top; the plates being reenforced by elongated, overlapping surface lugs forming a slip-proof surface and containing elongated apertures so shaped and positioned as to be available as emergency hand holds and forming draft vents for the deflection of snow and discharge openings for the drainage of water. The elongated apertures may be provided with peripheral flanges, which supplement the reenforcement provided by the lugs.

Preferably the plates are so supported, relatively to the car top, as to provide therewith a substantially unobstructed passage from end to end of the car, so that air currents, flowing through such passage, swirl upward through the elongated slots throughout the length of the running board and divert the fall of snow therefrom.

The characteristic features and advantages of my improvements will further appear from the following description and the accompanying drawings in illustration thereof.

In the drawings, Fig. 1 is a fragmentary top plan view of a freight car having a running board applied thereto in accordance with my invention; Fig. 2 is an end view looking in the direction indicated by the line and arrows 2—2 in Fig. 1; Fig. 3 is a transverse sectional view taken on the line 3—3 of Fig. 1; Fig. 4 is a fragmentary longitudinal sectional view showing the juncture of two plates on a hollow saddle permitting substantially unobstructed wind sweep under the walkway; Fig. 5 is an enlarged fragmentary top plan view of a section of rolled steel plate used in my improved walkway; Fig. 6 is a transverse sectional view on the line 6—6 of Fig. 5 but on a smaller scale; Fig. 7 is a fragmentary view showing a modified connection of longitudinal and latitudinal runway; Fig. 8 is a fragmentary transverse sectional view of the modified mounting of the latitudinal runway; Fig. 9 is a frag-

5
mentary top plan view of a runway section containing flanged apertures; Fig. 10 is a transverse sectional view of the runway section shown in Fig. 9; and Fig. 11 is a longitudinal sectional view of the runway section shown in Fig. 9.

In the drawings, my improvements are shown applied to a usual freight car roof having sections 1 and 2 inclined upwardly from the longitudinal edges of the car to a median longitudinal ridge 3 (see Figs. 2 and 3).

Along this ridge there is mounted a longitudinal running board composed of rigid rolled steel plates 4, 5, 6, each having down-turned flanges along the longitudinal edges thereof. The end plates 4 and 6 also have transverse down-turned flanges at the outer ends thereof.

20
Each of the rigid rolled plates 4, 5 and 6 is reenforced by integral elongated protuberant bosses 9 rolled on the upper surface thereof and preferably consisting of transversely disposed substantially lozenge-shape studs or projections arranged in rows lying normal to one another; each set of rows extending diagonally across the plate. The elongated studs of each diagonal row 25 are separated by elongated studs of diagonal rows normal thereto and the rows so overlap one another that no straight line can be drawn transversely across the plate which is not intersected by a series of such reenforcing studs.

Each plate contains a series of rows of staggered elongated slots 10 and 11 spaced laterally and longitudinally from one another so that the areas of the apertures in the flat longitudinal walkway constitute at least ten percent 30 of the total area thereof but there is an imperforate section of plate normal to the edges thereof between planes bounding adjacent ends of each transverse row of apertures 10 and a transverse row of apertures 11. The edges of the 35 apertures are haphazardly reenforced by sections of lugs 9, and the ends of the slots are curved so that the danger of cracking is minimized and any cracks which may develop are quickly stopped by a lug.

40
45
50
55
As illustrated in Figs. 9, 10 and 11, the edges surrounding the slots may be bent downward to provide reenforcing bossed flanges 10a and 11a and preferably portions of the flanges of adjacent rows 10a and 11a lie in the same transverse plane taken through the thickness of the sheet. The reenforcement against stresses normal to the sheet edges thus provided by the overlapping of the planes of the ends of the flanges 10a and 11a permits the rows of slots 10 and 11 to be placed in closer juxtaposition in a sheet of given thick-

ness than is desirable in a sheet of that thickness when the edges surrounding the slots are not flanged.

The plates 4, 5 and 6 are preferably supported above the plane of the ridge 3 by suitable brackets. For instance, the outer ends of the plates 4 and 6 may be supported by bent brackets 12 secured to the downturned end flanges of the plates and to the ends of the car; the abutting ends of the plates 4, 5 and 6 may be supported by yoke-like brackets 13 having top sections fitting between the side flanges of such plates and having ears 14 connected with the roof sheets or frame beyond the sides of the runway; and the intermediate sections of the plates 4, 5 and 6 may be supported by brackets or clips 15 and 16 having bent uprights secured to the side flanges of the plates and ears secured to the roof sheets or frame beyond the sides of the runway.

Latitudinal runways are provided adjacent to the ends of the car roof and, as shown in Figs. 1 and 2, such latitudinal runways may consist of rigid rolled steel plates 7 and 8 reinforced by lozenge-shaped bosses 9 and containing rows of slots 10 and 11. The slots may have plain cut edges as illustrated in Figs. 5 and 6, or flanged edges as shown in Figs. 9 to 11. The plates 7 and 8 may have plain edge sections to facilitate the riveting thereof to bracing strips attached to the car roof, and may also be provided with downturned outer lips or flanges and upturned inner lips or flanges nesting under side flanges of the plates 4 and 6, and with usual hand hold irons 17, as shown in Figs. 1 and 2.

Sometimes, however, it is preferable that the latitudinal walkways, as well as the longitudinal walkway, be supported sufficiently above the surface of the car roof to provide a sweep of air beneath the latitudinal walkways, as illustrated in Figs. 7 and 8. As illustrated in these figures, there may be provided, at each end of the car, a latitudinal walkway comprising a rigid rolled steel plate 1a having side flanges, reinforcing surface bosses 9, and a series of slots 10 and 11 similar to those of the plate section shown in Figs. 5 and 6 or in Figs. 9 to 11. The inner end of each plate 1a is supported by a pair of brackets 18 having upturned ears 19 fixed to the side flange of the longitudinal walkway and ears 20 fixed to the side flange of the latitudinal walkway. The outer end of each latitudinal walkway is supported by a pair of brackets 21 fixed to the under-side of the walkway and to the side of the car.

It will be observed that the running board operates with the inclined car roof sheets to form a longitudinal passage extending substantially unobstructed from end to end of the car and decreasing laterally in cross-section toward the longitudinal center line or ridge of the car, so that wind sweeping along the car roof, due to its motion or otherwise, is caused to form drafts through the openings 10 and 11, whose curved ends tend to swirl the drafts and prevent the accumulation of falling snow on the running board and permit the drainage of water from the running board. The roughened surface provided by the bosses and openings afford secure non-slip footing. In the embodiment of the invention illustrated in Figs. 7 and 8, the air currents also pass under the latitudinal walkways and sweep upward through the slots therein.

The openings 10 and 11 in the plates are of such width and length as to provide emergency

hand holds when the plates are spaced above the car roof, but do not obstruct or detrimentally weaken the running board, which may be made of comparatively thin rolled steel plate, say $\frac{1}{8}$ inch in thickness, due to the rigidity imparted thereto by the relative positioning and spacing of the protuberant lugs and slots and the flanges surrounding the latter. Moreover, the rigidity of the running board and the manner of its attachment with the car roof coacts with the latter to form a box-like section extending longitudinally of the car and materially increasing the rigidity of the roof structure.

Having described my invention, I claim:

1. A car roof running board comprising rigid rolled steel plate containing oblongish slots of a size suitable for use as hand holds in staggered relation to one another and transversely reinforced by overlapping elongated bosses, said slots having their lengths extending longitudinally of the running board and the lengths of said bosses extending diagonally relatively to the lengths of said slots.
2. The combination with an inclined car top, of a running board extending longitudinally of the top and composed of rigid rolled steel plate forming a flat surface the full width of the running board and containing rows of longitudinally extending vents of a size suitable for use as hand holds and providing drafts for air currents flowing between said plates and inclined top and transversely reinforced with integral overlapping elongated bosses extending transversely to one another and diagonally of the length of the plate.
3. The combination with a car roof having sections inclined upwardly from the car edges toward the longitudinal center line of the roof, of a walkway extending from end to end of the car roof and forming therewith a substantially unobstructed passage from end to end of the car, said walkway comprising rigid rolled steel plate transversely reinforced by integral surface bosses and containing longitudinally extending rows of staggered oblongish vents of a size suitable for use as hand holds and providing drafts for air currents sweeping through said passage, said vents having curved ends, and brackets supporting said plates without substantially obstructing the passage thereunder.
4. A car roof running board comprising rigid rolled steel plate transversely reinforced by diagonal rows of integral lugs and containing slots of a size suitable for use as hand holds having substantially parallel edges each intersecting a plurality of said lugs and reinforced by intersected lugs aforesaid.
5. The combination with a car roof structure, of a running board comprising a slotted flanged rigid web transversely reinforced by surface bosses and forming with the roof structure a box like section extending longitudinally of the roof and forming a substantially unobstructed passage, and brackets anchored to said roof structure beyond the edges of said running board and supporting said web without substantially obstructing said passage.
6. A car roof running board comprising rigid rolled steel plate reinforced by protuberant integral bosses and containing slots of a size suitable for use as hand holds, the plate edges surrounding said slots being flanged downwardly a distance not exceeding half the width of the respective slots.
7. A car roof running board comprising rigid rolled steel plate reinforced by integral protu-

berant bosses and containing transverse rows of staggered slots, the plate edges surrounding said slots being flanged and portions of the flanges of adjacent rows being intersected by a plane extending across the plate normal to the edges thereof.

8. A car roof running board comprising rigid rolled steel plate reinforced by integral protuberant bosses and containing transverse rows of

5 staggered slots of a size suitable for use as hand holds, the end edges of one transverse row of slots being separated from the adjacent end edges of the next transverse row of slots by an imperforate strip of plate normal to the edges thereof and reinforced by bosses extending transversely to one another.

LEON J. LIEBERMAN.
